No. 37,341.

Patented February 14, 1905.

UNITED STATES PATENT OFFICE.

JAMES B. ZINK, OF TERRELL, TEXAS.

DESIGN FOR A WORK-TABLE.

SPECIFICATION forming part of Design No. 37,341, dated February 14, 1905.

Application filed January 19, 1905. Serial No. 241,896. Term of patent 14 years.

To all whom it may concern:

Be it known that I, JAMES B. ZINK, a citizen of the United States, residing at Terrell, in the county of Kaufman and State of Texas, have 5 invented a new, original, and ornamental Design for a Work-Table, of which the following is a specification, reference being had to the accompanying drawing, forming part thereof.

The figure is a perspective view of a work-table, showing my new design.

What I claim as new, and desire to secure by Letters Patent, is—

The ornamental design for a work-table, as shown.

JAMES B. ZINK.
